(57) **CLAIM**

The ornamental design of a light emitting diode (LED) module for a lighting device, as shown and described.

DESCRIPTION

FIG. 1 is a top view of a light emitting diode (LED) lens module for a lighting device.

FIG. 2 is a bottom view of the LED lens module.

FIG. 3 is a first side view of the LED lens module.

FIG. 4 is a second side view of the LED lens module.

FIG. 5 is a third side view of the LED lens module.

FIG. 6 is a fourth side view of the LED lens module.

FIG. 7 is a first perspective view of the LED lens module; and,

FIG. 8 is a second perspective view of the LED lens module. In the drawings, the broken lines are shown for illustrative purposes only and form no portion of the claimed design.
